poration of Illinois

Application March 17, 1937, Serial No. 131,295

3 Claims. (Cl. 123—193)

This invention relates to pistons, and more particularly to internal combustion engine pistons of aluminum alloy or other light weight metal having a relatively high coefficient of expansion.

5 A highly important consideration in the design and construction of pistons for internal combustion engines is the provision of means for dissipating heat from the pistons to maintain the same within the desired temperature range during 10 engine operation. Provision for adequate heat dissipation is especially important in pistons used in two cycle engines, or engines having a relatively large cylinder diameter, or any type wherein the amount of power generated is great as compared to the surface area of the cylinder available 15 for the transfer of heat from the piston. An overheated piston tends to cause improperly timed firing of the fuel charge. Furthermore, where pistons formed of aluminum alloy or other metals 20 having relatively high coefficients of expansion are employed, adequate heat dissipation from the piston, or temperature control thereof is necessary in order to maintain proper operating clearance between adjacent surfaces of the piston and 25 cylinder.

As conventionally constructed, the head end of the piston, or that part in the vicinity of the piston rings, does not make rubbing contact with the cylinder walls and therefore heat must travel from 30 the high temperature piston head to the relative cooler cylinder walls through the piston rings and through the skirt end of the piston.

An object of the present invention resides in the provision of a piston for an internal combustion engine, embodying improved means for augmenting the flow of heat therefrom, and especially from the head end of the piston. In addition to the aforesaid function of the means which constitute in part the subject matter of the 40 present invention, such means also serve automatically to size the head end of the piston to the particular cylinder which receives the same, in fulfillment of another object of the invention.

In the following description setting forth a preferred piston construction whereby the foregoing objects are attained, the lands adjacent the grooves for the piston- or packing-rings are provided with narrow circumferential ribs which project outwardly a small distance beyond the side 50 surface of the piston. These narrow ribs contact the inner wall surface of the cylinder, tending to flow or wear when the engine is operated for the first time. The ribs are quickly sized by coaction with the cylinder wall, or reduced to 55 the most desirable operating diameter, and being

in direct contact with the cylinder wall provide a short path through which an appreciable amount of heat from the piston head is dissipated.

Stated generally, the object of the invention is to provide a piston embodying improved means 5 for dissipating heat, and constructional features which result in an operating fit between the cylinder and piston closely approaching the ideal.

Other objects and advantages will appear from the following detailed description and accompanying drawing which shows a piston constructed in accordance with the present invention.

Fig. 1 is a sectional elevational view showing a fragmentary portion of a cylinder with the piston, devoid of packing rings, therein; Fig. 2 is a top plan view of the assembly shown in Fig. 1; Fig. 3 is a bottom plan view of the piston, and Fig. 4 is a transverse sectional view of the piston, the section being taken at line 4—4 of Fig. 1.

My improved piston, preferably initially formed 20 as an integral casting of aluminum alloy, is characterized by a head structure which includes a top plate 5 and a tubular side-wall portion 6, depending from the margins of the top plate a sufficient distance to accommodate a plurality of 25 piston rings (not shown). The wall portion 6 merges into a tubular extension or continuation thereof, preferably of reduced wall thickness, which constitutes the piston skirt 7.

Projecting from diametrically opposite sides, 30 internally of the piston, are bosses 8 which are provided with aligned bores therethrough to accommodate the ends of a wrist pin (not shown). Ribs 9 extending between bosses 8 and top plate 5, aid in transmitting the thrust forces imparted 35 to the piston head to the wrist pin and otherwise serve to reinforce the piston structure. One of the bosses 8 is provided with a transverse bore 10 which, when suitably threaded, is adapted to receive a set screw or the equivalent for preventing axial displacement of the wrist pin. Formed on the inner side-wall surface of the piston are a series of fins 11 which extend longitudinally of the piston and project radially inwardly from its side wall. The fins 11 aid materially in conducting 45 and radiating heat away from the relatively high temperature piston head, the heat being transferred through the skirt 7 to the cylinder walls and, particularly in the case of a two-cycle engine, to the incoming fuel vapor and lubricating oil in the engine crankcase.

To allow for lateral expansion of the side walls under operating conditions, resulting in large measure from expansion of the pin bosses 8, the outer surface of the skirt 7 is machined to pro- 55

vide appreciable relief at areas in the vicinity of the pin bosses, the relieved areas, indicated at 12, Fig. 4, extending the full length of the piston skirt. This machining process, termed 5 "cam grinding", results in a pair of lands, designated 13, located on the outer skirt surface midway between the pin bosses, the lands 13 extending longitudinally of the piston from the lower extremity thereof approximately to the locality 10 where the skirt merges into the piston head. The diameter of the piston between the land surfaces is such that small tolerance or clearance is allowed between the coacting lands and cylinder walls, thus providing for closely fitting surfaces 15 at those areas of the cylinder wall where lateral components of piston thrust are directed. The lands 13 further provide paths of substantial surface extent for conducting heat from the piston to the cylinder wall.

20 As in the case of pistons of conventional construction, the diameter of the head end of the piston is slightly reduced, thereby providing for an appreciable clearance between the piston head and cylinder and avoiding rubbing contact 25 between these parts in the vicinity of the packing rings. Rubbing contact is, of course, present between the packing rings and cylinder, and in conventional piston assemblies, the packing rings provide the only direct path for the flow of heat 30 from the piston to the cylinder wall.

For the purpose of augmenting heat flow from the piston head and improving the operating fit between the piston head and cylinder, in carrying out a stated object of the present invention, the 35 lands 14 between and adjacent the ring grooves 15 are provided with narrow bands or ribs 16 which are preferably formed integrally with, and project laterally outwardly from the surface of the said lands. The initial diametral dimension of 40 the ribs 16, prior to any change thereof resulting from wear, is such as to provide for a snug fit with the cylinder bore. In the early stages of engine operation the ribs 16 wear, flow, or otherwise quickly reduce themselves to an ideal working diameter. Tests have proven that these narrow ribs do not cause scoring of the cylinder surfaces or in any way produce harmful effects. The confronting surfaces of the cylinder and ribs 45 16 remain bright after long operating periods, indicating substantially frictionless metal to metal contact, a favorable condition for dissipating heat from the piston head.

The piston illustrated in the accompanying drawing is adapted for use in a two-cycle engine 55 and accordingly is provided with a deflector, or baffle 17 for preventing the fuel vapors from passing from the inlet port, directly across the cylinder bore to the outlet port. As heretofore designed and constructed the opposite ends of deflector 17 are spaced an appreciable distance 60 from the cylinder wall, and under no circum-

stances is contact effected between the deflector ends and the cylinder. Being disposed within the firing zone, the deflector is subjected to exceedingly high temperatures and it is desirable to provide a direct path for heat flow, to the 5 end of dissipating heat therefrom. Accordingly, in my improved piston, the deflector is tapered at its opposite ends and terminates in relatively narrow prolongations 18 which are adapted to contact the cylinder wall. The prolongations 18 are 10 sized to the cylinder in the same manner as are the ribs 16, previously described.

The substance of my invention is set forth in the following claims, but it is understood that various changes or modifications within the pur- 15 view of my invention may be made in the construction illustrated in the accompanying drawing and description above.

I claim:

1. A piston for use in the cylinder of an internal combustion engine, having head and skirt portions, an integral baffle member extending across said head portion, said baffle member having relatively thin prolongations of ductile metal adapted to contact the wall of the cylinder during 20 engine operation.

2. A piston for use in a cylinder of a two-cycle internal combustion engine, having head and skirt portions, the head portion of said piston having circumferential grooves for receiving 30 packing rings, and an integral baffle member extending across the top thereof, thin circumferential ribs of ductile metal projecting laterally from the piston adjacent said ring grooves, and thin prolongations of ductile metal at opposite 35 ends of said baffle member, said ribs and prolongations being adapted to contact the cylinder walls during engine operation.

3. An aluminum alloy piston for use in the cylinder of a two-cycle internal combustion engine, 40 said piston comprising integral head and skirt portions of diameter appreciably less than the bore diameter of the cylinder with which the piston is to be used, a baffle member formed on the top surface of said head portion, the opposite ends of said baffle member being relatively 45 narrow and adapted to contact the cylinder wall, grooves for packing rings formed in said head portion, circumferential ribs projecting laterally outwardly, adjacent said ring grooves, said ribs 50 being adapted to contact the cylinder walls, pin bosses projecting inwardly from diametrically opposite side surfaces of the piston, lands extending longitudinally of the outer skirt surface, 55 spaced between said pin bosses, said lands being adapted to contact the cylinder walls, and a series of radial, inwardly projecting fins extending along the inner side surfaces of said head and skirt portions.

WILLIAM C. DEHN. 60
